UNITED STATES PATENT OFFICE.

HARRY F. EVANS, OF DAVENPORT, IOWA, ASSIGNOR TO DEERE & COMPANY, OF MOLINE, ILLINOIS, A CORPORATION OF ILLINOIS.

WEARING-PLATE FOR MOWING-MACHINES.

1,276,195.

Specification of Letters Patent. Patented Aug. 20, 1918.

Application filed December 1, 1915. Serial No. 64,518.

To all whom it may concern:

Be it known that I, HARRY F. EVANS, a citizen of the United States, and a resident of Davenport, in the county of Scott and State of Iowa, have invented certain new and useful Improvements in Wearing-Plates for Mowing-Machines, of which the following is a specification, reference being had to the accompanying drawings.

10 This invention relates to wearing-plates used in connection with the sickle of a mowing machine and adapted to receive the backward and downward pressure of the sickle as it is reciprocated in operation. It is one 15 of the objects of my invention to provide a wearing-plate of this type so arranged as to be adapted to present either of two wearing parts for contact with the sickle, whereby the plate is made operative in a plurality of reversed positions. By the use of 20 my expedient I am enabled to provide a reversible plate of this character by the use of a very small amount of additional material at a substantially negligible increase 25 in cost, serving to double the life of the wearing-plate. This expedient has the additional advantage that when one of the wearing surfaces becomes worn another operative wearing part is immediately available 30 without any possible question as to where a repair or exchange plate has been stored for safe keeping pending its use. It is another object of my invention to improve mechanisms comprising finger-bars, sickles 35 and wearing-plates in sundry details herein-after pointed out. The preferred means by which I have accomplished the objects of my invention are illustrated in the accompanying drawings and are hereinafter specifically 40 described. That which I believe to be new and desire to cover by this application is set forth in the claims.

In the drawings, Figure 1 is a fragmentary top view showing the connection 45 between the finger-bar and the inner shoe by which the finger-bar is carried;

Fig. 2 is a vertical cross-section through the finger-bar, being taken substantially on line 2—2 of Fig. 1; and

50 Fig. 3 is an enlarged detail, being a perspective view of one of the wearing plates.

Referring to the several figures of the drawings, in which corresponding parts are indicated by the same reference characters,—

10 indicates the inner shoe of a mowing machine adapted to be connected in position by means of perforated lugs or ears 11—12. A finger-bar 13 is secured at its inner end to the shoe 10 by means of bolts 14,—a wearing-plate 15 and a keeper 16 being secured 15 by said bolts in position above the end of the finger-bar. It will be understood that in a complete machine a plurality of wearing-plates and keepers are employed, spaced at intervals along the finger-bar 13, as is the 20 ordinary practice.

The sickle employed is of the ordinary type comprising a bar 17, blades or sections 18 riveted thereto, and an operating head 19 secured upon the inner end of the bar 17. 25 The rear edges of the sections are shown extending beyond the rear edge of the sickle-bar, providing thus a longitudinally-extending rib at the rear upper edge of the sickle. The head 19 extends to the rear between the 30 wearing-plate 15 and the keeper 16, as best shown in Fig. 2, and extends forward as best shown in Fig. 1 underneath a keeper 20 carried by the shoe 10 whereby the inner end of the sickle is held in proper operative 35 position. The sickle is adapted to be operated in the ordinary manner by means of a pitman connected by suitable socket means with a ball 21 forming a part of the head 19. As in ordinary practice, guards 22 are 40 mounted upon the finger-bar 13 at intervals, the guards 22 being provided with ledger-plates 23 provided with cutting edges adapted to coöperate with the cutting sections 18 45 of the sickle, as is well understood in the art. 45 A ledger-plate 23 is also carried by the shoe 10, as shown in Fig. 2, adapted to coöperate with the innermost section 18 of the sickle. The keeper 16 at the inner end of the finger-bar 13 is provided with a perforated arm 24 50 for controlling the position of the finger-bar 55 as may be desired.

As is best shown in Fig. 2, the wearing-plate 15 is provided with a downwardly-extending flange 25 at its forward edge forming an angle which fits over the forward edge of the finger-bar 13. The sickle-bar 17 bears at its rear edge against the flange 25, while the under faces of the blades or sections 18 bear upon the upper face of the 100 wearing-plate at its forward edge. In the construction shown, the wearing-plate 15 is also provided at its rear edge with an up-

wardly-extending flange 26. As will be readily understood, when the portions of the wearing-plate 15 which are in contact with the sickle-bar 17 and the blades 18 of the sickle become worn by reason of the backward and downward pressure thereon in use, the plate 15 is adapted to be removed and easily and quickly replaced with the flange 26 in position to take the backward pressure of the sickle-bar 17. Thus by the use of the construction illustrated, by means of the very small additional amount of material involved in the provision of the flange 26, the life of the wearing-plate 15 as an effective element of the construction is doubled.

So far as I am aware, I am the first in the art to provide a Z-shaped wearing plate either flange of which may be used as desired for receiving the wear of the sickle, and the first to provide a wearing plate having flanges at its opposite edges whether of a Z form or not which can be used with either flange as desired positioned along the forward edge of the finger bar and adapted

in such position to receive both the backward and the downward pressure of the sickle, and my claims are to be construed accordingly.

That which I claim as my invention, and desire to secure by Letters Patent, is,—

1. A reversible wearing-plate for mowing-machines, said plate having a flange extending substantially at right angles to the plate along each of its front and rear edges so that either flange may extend into the space between adjacent edges of a finger-bar and sickle-bar when the plate is in position upon the machine.

2. A reversible wearing-plate for mowing-machines, said plate having a flange at each of its front and rear edges extending substantially at right angles from the plate and in opposite directions so that either flange may extend into the space between adjacent edges of a finger bar and sickle-bar when the plate is in position upon the machine.

HARRY F. EVANS.
